UNITED STATES PATENT OFFICE

2,677,391

PRESSURE AND/OR VACUUM DISTRIBUTOR

Walter F. Chellberg, Valparaiso, Ind.

Application May 27, 1949, Serial No. 95,773

9 Claims. (Cl. 137—624)

1

This invention comprises novel and useful improvements in a pressure and/or vacuum distributor for pressure or vacuum and more specifically pertains to an easily reversible rotary distributor valve for selectively distributing a medium under pressure or vacuum in predetermined sequence from a common source of pressure or vacuum to various places of use such as particularly to the cylinders of steam engines, air motors and the like.

The principal object of the invention is to provide an improved means for selectively connecting a source of pressure or suction in a predetermined sequence with a plurality of individual users of the pressure or vacuum medium and in particular in an improved and advantageous manner in which the sequence of delivery may be readily reversed.

A further important object of the invention is to provide a rotary reversible distributor of a simplified construction which is particularly adapted to economical manufacture, and yet will be exceedingly compact and will form a unitary assembly.

An important feature of the invention resides in the provision of a device having a single rotatable member for selectively establishing communication between the various conduits leading to the consumers of the pressure or vacuum medium and with the source of supply; together with a concentric member interposed between the rotatable distributing member and the conduits, which concentric member is manually adjustable to reverse the sequence of distribution.

More specifically, the invention comprises a reversible rotary distributing valve which will deliver pressure or vacuum from a source such as a pump to the cylinders of a motor such as a steam engine, air motor, vacuum motor, hydraulic motor or the like, in predetermined sequence; and wherein the direction of rotation of the motor may be readily reversed by merely reversing or angularly adjusting the reversing valve interposed between a rotary distributing valve and the passages leading to the various pressure or vacuum consumers.

Another very important feature of the invention resides in the provision of a pressure or vacuum distributing valve assembly which is provided with two sets of ports, which are spaced at equal angular intervals, one set of ports being employed for delivery of the medium in a first predetermined sequence, and the other set of ports being employed for delivering the medium in a reversed sequence.

2

Further features of the invention reside in the provision of a distributing valve mechanism which shall be of simple and compact construction, may be easily manufactured in an inexpensive manner, and which shall be highly efficient for the purposes intended.

These, together with various ancillary objects of the invention which will later become apparent as the following description proceeds, are attained by this device, a preferred embodiment of which has been illustrated by way of example only in the accompanying drawings, wherein:

Figure 1 is a side elevational view, showing a preferred embodiment of the distributing valve assembly in accordance with this invention;

Figure 2 is an end view of the arrangement shown in Figure 1, parts being broken away;

Figure 3 is a transverse vertical sectional view taken substantially upon the plane of the section line 3—3 of Figure 4 and showing particularly the exhaust manifold construction of the valve assembly;

Figure 4 is a vertical longitudinal sectional view taken through the arrangement of Figure 1, the manual reversing handle being removed therefrom;

Figure 5 is a group perspective view showing in separated arrangement, certain of the operative parts of the valve mechanism, the direction of flow of the pressure or vacuum medium through the valve, for a predetermined sequence of operation which may be termed the forward rotation of the valve, being indicated by the arrows therein;

Figure 6 is a further vertical transverse sectional detail view taken substantially upon the plane of the section line 6—6 of Figure 4 and illustrating one of the distributing manifold arrangements of the invention;

Figure 7 is another detail vertical transverse sectional view taken substantially upon the vertical plane of the section line 7—7 of Figure 4 and illustrating another manifold arrangement forming a part of the invention;

Figure 8 is a vertical longitudinal sectional view through the valve, showing the valve in a different position during its operation;

Figure 9 and Figure 10 are diagrammatic views illustrating the operation of the intake and exhaust manifolds of the distributing valve disk in their relation to the two sets of ports and passages and to the manifold assemblies associated therewith;

Figure 11 is a fragmentary perspective view, parts being broken away, showing a portion of the

valve assembly, the distributing valve, the reversing valve disk, and the valve manifold assemblies; and

Figure 12 is an elevational view taken substantially upon the plane of the section line 12-12 of Figure 4.

In the accompanying drawings, like numerals designate similar parts throughout the various views, wherein the specific construction and operation of the improved reversible rotary valve assembly is disclosed. The reversible rotary distributing valve for pressure or vacuum disclosed herein is applicable to a plurality of environments requiring the timed, and sequential delivery in a predetermined order of a series of pressure or vacuum impulses such for example as steam engines, air motors, hydraulic motors, and any other apparatus employing pressure or vacuum pulsation in timed relation. It is evident that the connecting of the conduits of the rotary valve to the particular environment desired is a matter which resides within the skill of the mechanic, and therefore such connections have not been deemed necessary of illustration in the present application.

Referring first primarily to Figures 1 and 4, it will be seen that the rotary distributing valve assembly indicated generally by the numeral 40 is provided with an axial valve operating shaft 41 which may be connected with any suitable driving means such as that shown in Figures 4 and 12 whereby the operation of the valve may be driven by the apparatus with which it is to be associated in properly timed relation. Secured to the end of shaft 41 is a coupling sleeve 43 having a chamber 45 with a radial enlargement 47 adapted to receive the key on a driving shaft. The enlargement has an arcuate extent of 45° plus the width of the key so that the shaft 41 will have a rotational adjustment of 45° when the direction of rotation is reversed. The coupling 43 may be secured to shaft 41 as by an internally splined connection 49.

Indicated at 42 is a conduit which connects the valve assembly 40 with any suitable source or pressure or vacuum as desired. The conduit 42 may be thus regarded as the intake of the valve assembly 40, by means of which the impulses are supplied to the distributing valve for delivery therefrom while a further conduit 44 constitutes an exhaust or return conduit by means of which the discharge or return exhaust flow from the member supplied with the pressure or vacuum from the valve assembly may be either returned to the intake side of the source, not shown, or may be discharged to the atmosphere as preferred. Hereinafter, conduit 42 may be referred to as the pressure or fluid intake of the valve assembly 40, while conduit 44 is regarded as the exhaust or return conduit of the valve assembly.

A plurality of delivery conduits indicated at 46, 48, 50 and 52 extend from the valve assembly 40 to various places of use of the pressure or vacuum distributed by the rotary valve. These four conduits serve both as a means for delivering the impulses to the place of use, and for returning the medium from the place of use to the exhaust manifold assembly within the casting 40, from whence exhaust is effected by means of the conduit 44 previously mentioned.

As shown in Figures 4, 5 and 8, the distributing valve assembly has as its main portion a stationary cylindrical body 54 provided terminally with a diametrically reduced extension 56, and 75 will overlie and render inoperative the other set

with an axially extending diametrically reduced sleeve 58. An axial bore 60 is provided in the body, in the reduced portion 56 and in the sleeve 58 and constitutes a journal bearing for the previously mentioned shaft 41.

The sleeve 58 and the extension 56 are externally screw threaded on their opposite ends 66 and at 68 respectively.

Screw threadedly engaged upon the threads 10 68, is a cap member 70, see Figures 4 and 8, which serves as a closure member and also as a chamber for receiving the distributing valve disk and the reversing valve disk as set forth hereinafter.

A plurality of longitudinally extending passages 71 are formed in the valve body 54, these passages being disposed parallel to and equidistantly spaced from the axial bore 60, and at equal angular intervals with respect to each other, these apertures being of any desired number, eight being shown in the example illustrated in the drawings, and these apertures for convenience of designation are indicated and hereinafter referred to as A, B, C, D, E, F, G and H, these letters also referring to the corresponding 20 aligned bores and passages to be referred to hereinafter. The passages 71 constitute both the delivery passages of the valve assembly for the pressure or vacuum and the return passages therefor.

As shown best in Figures 4 and 5, the valve body 54 is likewise provided with a radially extending passage 72 to whose outer extremity is connected the previously mentioned exhaust or discharge conduit 44. At its inner extremity, 35 the passage 72 terminates in an arcuately disposed port 74 which constitutes the exhaust port for the valve body.

Rotatably journaled in the bore 60 is a sleeve 40 76 which extends beyond the screw threaded extension of the sleeve 58, at one end, and at its other end extends through the body 54 and the reduced portion 56, and is provided with an integral reversing valve disk 78. The disk 78 is provided with four longitudinally extending distributing passages or ports 80 which are disposed 45 at 90° intervals and equidistantly from the axis of the valve disk.

It should be here noted that the number of 50 distributing ports 80 in the reversing valve disk 78 will correspond to the number of pressure or vacuum impulses which it is desired to deliver from one cycle of rotation of the distributing valve, and since the valve illustrated contains eight distributing passages 71, there will be but 55 four distributing ports 80. In other words, there will be half as many ports 80 as there are passages 71, it being here noted that one half of the passages 71 will be employed for one direction of rotation of the distributing valve, and the other half of the passages will be employed for the reverse rotation of the same.

The reversing valve disk 78 remains in a relatively fixed position with each of the four ports 80 registering with one set of bores or passages 65 71 in the valve body, but is manually oscillated or rotated by a means to be subsequently described, to an alternative position whereby the four ports 80 may register with the other set of distributing passages 71 for the reverse direction of rotation of the valve assembly.

It will be noted that the reversing valve disk 78 thus constitutes the selector for rendering operative one set consisting of four of the passages 71, while the solid portion of the disk 78 75 will overlie and render inoperative the other set

of passages 71 which is not being at that time employed. When the reversing disk 78 is rotated through, in this instance, 45°, the ports 80 will register with the second set of distributing passages, thus rendering the first set inoperative.

As will be seen from Figures 4 and 8, the reversing valve disk 78 lies flush against what may be termed the outer surface of the reduced portion 56 of the valve body 54, and a distributing valve disk 82 is disposed on the outer side of the reversing disk 78, being integrally formed upon the outer extremity of the driving shaft 41, the intermediate portion of the shaft 41 being rounded to have a bearing within the sleeve 76.

As shown best in Figure 5, the distributing valve disk 82 is provided with a pair of arcuate distributing ports 84 and 86, oppositely disposed, and constituting respectively a pressure or vacuum inlet port or manifold and the exhaust pressure port or manifold. Preferably, each of these ports extends through about 170° of arc and is struck upon a radius so that the ports will register with the bores 88, which in turn register with the distributing passages 71.

The exhaust manifold or port 86 is further provided with a radially extending passage 88 which, see Figures 4, 5 and 8, is adapted to overlie and register with an annular exhaust manifold 98 comprising an annular space positioned between the outer periphery of the reversing disk valve 78 and the inner periphery of an annular spacing member 92 which is clamped between the outer surface of the reduced portion 56 and a shoulder 94 on the cover 70 when the latter is screw threaded upon the body 54. While the intake manifold or port 84 extends entirely through the distributing valve disk 82, to thus communicate with the space within the cover member 70, and hence with the pressure or vacuum intake conduit 42, the exhaust manifold 86 and 88 are formed as recesses in the inner surface only of the distributing valve disk 82 and thus do not communicate with this space.

This port and manifold arrangement will be particularly evident from an inspection of Figure 11 which thus shows the relation of the various parts previously described.

As will be seen from Figures 4 and 8, the cover plate 70 is provided with an axially extending boss 96 which in turn is provided with a bore 98 on the inner side thereof, for the reception of a compression spring 100 which urges a ball member 102 against the axial or central portion of the distributing valve 82 to thereby urge yieldingly the valves 82 and 78 against each other and against the valve body portion 56 and thus maintain a tight seal therebetween to prevent leakage between the various ports and passages.

The intake chamber or manifold of the valve body is indicated at 104 as the space between the end wall of the cover member 70, and the adjacent surface of the distributing valve disk 82. This chamber 104 is at all times in free communication with a source of pressure or vacuum by means of the conduit 42, and likewise is at all times in communication with the intake port 84 of the distributor valve disk. The conduit 42 may be connected with the chamber 104 in any suitable manner as by a screw threaded aperture 106 therein.

Secured to the stationary valve body 54 are three annular members 108, 110 and 112, which are retained tightly thereagainst as by a locking nut 114 upon the threads 66 of the sleeve 53, whereby these annular members may be retained

in tight engagement with each other and with the body 54. Rotation between these various members is prevented as by a dowel pin 116 which extends through these three annular members and into the valve body 54 as shown in Figure 4.

It should be here noted that the members 108, 110 and 112 are formed as separate members solely for convenience of manufacture, since any of these various members could be formed integrally with the others and/or with the body 54.

Referring now particularly to Figure 5, it will be seen that the member 110 is provided with a plurality, in this instance eight, apertures 118 which respectively are aligned with the bore 71 in each of their positions A-H. Similarly, the member 108 is provided with eight longitudinal passages 120 which likewise are at all times in registry with the passages 71 of the body 54. Formed in its surface adjacent the disk member 110, see Figure 6, the member 108 has a pair of arcuate manifolds 122 and 124 which extend throughout about 170° of arc, and which are disposed radially outwardly of the series of passages 120, these two manifolds being connected with four of these passages as follows. The manifold 122 at its extremities has radially and inwardly extending passages 121 and 123 which connect with two of the ports 120 whereby either of these two ports may supply or deliver pressure or vacuum to the manifold 129. Similarly, the manifold 124 has radially inwardly extending passages 125 and 127 which connect with two other of the ports 120. Thus, four of the ports 120, are connected in pairs to the two manifolds 122 and 124. The latter also are provided with passages 129 and 131 to which the previously mentioned pressure or vacuum delivery conduits 50 and 52 are connected.

It is important to here note that the manifold 122 by means of the passages 121 and 123 is connected to one bore in each of the two sets of distributing passages. Thus, regardless of which of the two sets of distributing passages are rendered operative by the reversing valve disk 78, one of the passages 121 and 123 will be rendered operative while the other is inoperative. Thus, the conduit 50 will always be supplied with pressure or vacuum from whichever of the two sets of distributing passages are energized or rendered operative by the reversing valve. Similarly, the manifold 124 and conduit 52 are likewise provided with a passage which is operatively connected with one of the sets of distributing passages 71.

The face of the member 112 which is adjacent the plate 110 is similarly constructed, being provided with a pair of arcuately extending diametrically opposite manifold passages 126 and 128, each of which extends through about 170° of arc, and which as shown in Figure 7 are provided with radially inwardly extending terminal passages 133, 135 and 137 and 139. The passages 126 and 128 likewise communicate by means of radial passages 141 and 143 with the above mentioned pressure or vacuum delivery conduits 46 and 48.

It will be noted that the four passages of the manifolds 126 and 128 are connected with the other four bores 71 to which the manifolds 122 and 124 are not connected. Moreover, each of the manifolds 126 and 128 is connected to two of the conduits 71 by means of the radial passages, these being one conduit in each of the two sets controlled by the reversing valve.

The construction of the control means for the reversing valve disk will now be described. As shown in Figures 1 and 2, there is provided a

reversing and control lever 150 which is adjustably clamped as by a split hub 152 and a fastening bolt 154, upon the extremity of the sleeve 76 which carries the reversing valve disk 78.

Any conventional lever latch means may be provided for holding lever 150 in its adjusted positions, such for example as a stationary sector plate 156 which may be supported and mounted upon any convenient part of the mechanism with which the valve is associated, or even upon the valve assembly 40 if desired. This sector is provided with peripheral notches 158, 160 and 162 which respectively correspond to the forward, neutral or valve inoperative position and the reverse positions of the reversing disk which thus constitutes a valve control disk as well.

Slidable upon the lever 150 is a latch dog 164 having a latch wedge or blade 166 engageable selectively in the sector plate notches. A handle 168, pivoted to the lever at 170 is connected to the dog 164 by links 172 and a spring 174 urges the dog into latching position.

The operation of this particular latching mechanism is well known, and since the same forms no part of the invention herein claimed, further explanation as to construction or operation is deemed to be unnecessary.

From the foregoing construction, the operation of the valving assembly may now be understood. A pressure or vacuum is continuously maintained in the intake chamber 104 by means of the conduit 42. From the intake chamber 104, the pressure or vacuum medium is selectively admitted by means of the arcuate intake manifold slot 84 of the continuously rotating distributing valve disk 82, to predetermined sets of distributing passages 71, the intake valve port 84 being enabled to simultaneously contact or register with at least two of the ports 80 in the reverse and control valve disk 78. Since the port 84 extends throughout 170°, it is of sufficient length to at all times overlap three of the ports 71, and sometimes four of these ports as indicated in the diagrammatic view of Figure 9. However, by means of the reverse and control valve 78, only one set of four of the distributing passages 71 can be placed in communication with the intake port 84, the other set of passages being blocked off until such time as the reverse and control valve disk is shifted through 45°, to cause the four passages or ports 80 to register with the other set of passages 71.

With the control valve set for what may be termed the forward direction of rotation, the intake port 84 thus registers with two of the passages 71, such as those designated H and B in Figure 5. At the same time, the corresponding exhaust manifold port 86, by means of its passage 88, is placed in registry with the diametrically opposite port 71 from those which are overlapped by the port 84, to thereby establish communication with these exhaust registering passages and by means of the annular exhaust passage 90 and port 74, with the exhaust conduit 44. This arrangement is shown in the diagrammatic view of Figure 9. Thus, the pressure or suction of the medium is conducted by the intake manifold port 84, and the appropriate ports 80 in the control valve or reverse valve disk 78, and passages 71H and 71B, to the corresponding passages 120H and 120B, and as shown in Figures 9 and 10 the passage 120H is placed in communication with the intake manifold 124 and consequently with the delivery conduit 52 by means of

the radial passage 127; while the passage 120B extending through the corresponding aperture 118 of the disk 110, is likewise placed in communication by means of the radial passage 135 with the intake manifold 126 which is also in communication with the delivery conduit 46. Thus, the conduits 52 and 46 are subjected to the pressure or vacuum of the source, while in the same manner the conduits 48 and 50 by means of the exhaust manifolds 128 and 122 and the corresponding ports and passages are placed in communication with the exhaust conduit 44.

It will thus be seen that two of the four ports 80 of the reverse and control valve disk 78 are placed in communication with the source of pressure or vacuum, while two are placed in communication with the exhaust conduit. By this means, pressure or vacuum is continuously applied to two of the four conduits, while the previously applied pressure or vacuum in two of the other conduits is exhausted therefrom. As the valve 82 rotates, the intake and exhaust manifold ports 84 and 86 sequentially register with the predetermined set of distributing conduits 71 which are utilized in the forward direction of rotation, so that half of these conduits are subject to charging or intaking while the other half are subject to exhaust.

When it is desired to set the distributing valve 30 for reverse operation, it is merely necessary to properly actuate the lever 150, whereupon the control and reverse valve 78 is shifted through 45°, causing the ports 80 to now register with the corresponding passages 71 of the other set of distributing passages, H and B are now closed off, while the corresponding conduits A and C are placed in operation. The conduits A and C, are however in communication with the manifolds 122, 124 and 128, whereby the conduits 52 and 48 are subjected to the operating medium while the manifolds 122 and 126 are subjected to exhaust through the exhaust manifold port 86.

From the foregoing, the construction and operation of the device will be readily understood and further explanation is believed to be unnecessary.

However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having thus disclosed and described the invention, what is claimed as new is as follows:

1. A pressure or vacuum distributor comprising a casing having first and second sets of distributing passages and a plurality of delivery and return conduits, a passage of each of said sets being connected to each conduit, a rotary distributing valve journaled in said casing and having intake and exhaust ports registerable in sequence with each of said distributing passages, a reverse valve journaled in said casing and interposed between said distributing valve and said sets of passages and having arcuately spaced passages therein in selective alignment with one of said sets of passages for selectively establishing communication between said distributing valve ports and the distributing passages of one of said sets and adapted to be angularly adjusted for selectively establishing communication between said distributor valve ports and the distributing passages of the other of

said sets, a source of pressure or vacuum and an exhaust conduit and communicating means connecting said source and said exhaust conduit with the intake and exhaust ports of the distributor valve.

2. A pressure or vacuum distributor comprising a casing having first and second sets of distributing passages and a plurality of delivery and return conduits, a passage of each of said sets being connected by manifold means to each conduit, a rotary distributing valve journaled in said casing and having intake and exhaust ports registerable in sequence with each of said distributing passages, a reverse valve journaled in said casing and interposed between said distributing valve and said sets of passages and having arcuately spaced passages therein in selective alignment with one of said sets of passages for selectively establishing communication between said distributor valve ports and the distributing passages of one of said sets and adapted to be angularly adjusted for selectively establishing communication between said distributor valve ports and the distributing passages of the other of said sets, a source of pressure or vacuum and an exhaust conduit and communicating means connecting said source and said exhaust conduit with the intake and exhaust ports of the distributor valve.

3. A pressure or vacuum distributor comprising a body having a set of distributing passages, a set of delivery and return conduits, a source of pressure or vacuum and an exhaust conduit, a distributing valve rotatable in said body and selectively establishing communication between said set of passages and said source of pressure or vacuum and said exhaust conduit, manifold means connecting each of said passages with one of said delivery conduits, said manifold means comprising first and second body sections, openings in said first section each continuously in registry with one of said distributing passages, a reverse valve journaled in said body and interposed between said distributing valve and said passages, said reverse valve having arcuately spaced passages therein for selective alignment with said distributing passages for selectively establishing communication between said distributing valve and said distributing passages, intake and exhaust manifolds in the adjacent faces of said sections, each manifold communicating with one of said openings in said first section, each of said delivery conduits communicating with one of said manifolds.

4. A pressure or vacuum distributor comprising a body having a set of distributing passages, a set of delivery and return conduits, a source of pressure or vacuum and an exhaust conduit, a distributing valve rotatable in said body and selectively establishing communication between said set of passages and said source of pressure or vacuum and said exhaust conduit, manifold means connecting each of said passages with one of said delivery conduits, a control valve operatively interposed between said distributing valve and said delivery passages for selectively establishing and closing communication therebetween,

said manifold means comprises first and second body sections, openings in said first section each continuously in registry with one of said distributing passages, a reverse valve journaled in said

5 body and interposed between said distributing valve and said passages, said reverse valve having arcuately spaced passages therein for selective alignment with said distributing passages for selectively establishing communication between said distributing valve and said distributing passages, intake and exhaust manifolds in the adjacent faces of said sections, each manifold communicating with one of said openings in said first section, each of said delivery conduits communicating with one of said manifolds.

5. The combination of claim 1 wherein said manifold means comprises first and second body sections, openings in said first section each continuously in registry with one of said distributing 20 passages, a reverse valve journaled in said body and interposed between said distributing valve and said passages, said reverse valve having arcuately spaced passages therein for selective alignment with said distributing passages for selectively establishing communication between 25 said distributing valve and said distributing passages, intake and exhaust manifolds in the adjacent faces of said sections, each manifold communicating with one of said openings in said first section, each of said delivery conduits communicating with one of said manifolds.

6. The combination of claim 1 wherein said casing has an annularly reduced extremity, at one end, a cup-shaped member secured to said one end and forming an intake chamber there-with, said source of pressure or vacuum and said distributing valve communicating with said intake chamber.

7. The combination of claim 1 wherein said casing has an axial bore, said distributing passages being parallel to and equidistant from said bore, said distributing valve including a valve disk having means for effecting continuous rotation of the disk, said disk having ports registerable with said distributing passages.

8. The combination of claim 1 wherein said body has an axial bore, said distributing passages being parallel to and equidistant from said bore, said distributing valve including a valve disk having ports registerable with said distributing passages and a stem journaled in said bore for rotating said valve.

9. The combination of claim 8 wherein said reverse valve includes a sleeve journaled in said bore and upon said stem, and manual adjusting means secured to said sleeve angularly oscillating said reverse valve.
